UNITED STATES PATENT OFFICE

150,754

DESIGN FOR A TIRE

William Louis Cavin, Terrell, Tex., assignor of
one-half to Frank H. King, Terrell, Tex.

Application February 14, 1947, Serial No. 136,916

Term of patent 14 years

(Cl. D90—20)

To all whom it may concern:

Be it known that I, William Louis Cavin, a citizen of the United States, residing at Terrell, in the county of Kaufman and State of Texas, have invented a new, original, and ornamental Design for a Tire, of which the following is a specification, reference being had to the accompanying drawing, forming part thereof.

Figure 1 is a perspective view of a tire, showing my new design, and

Figure 2 is a fragmentary perspective view, showing the same in detail.

The essential features of the design reside in the portions shown in full lines, these features being continued circumferentially on the tire, as indicated by the phantom lines in Figure 1.

I claim:

The ornamental design for a tire as shown and described.

WILLIAM LOUIS CAVIN.
